APPARATUS FOR DRY CLEANING

Charles G. Watson, Youngstown, Ohio

Application June 26, 1933, Serial No. 677,625

2 Claims. (Cl. 68—18)

This invention relates as indicated to a method of and apparatus for dry cleaning, but has reference more particularly to certain improvements in the usual cleaning processes and in the 5 construction of various units of the apparatus employed therein.

A primary object of the invention is to provide a compactly arranged dry cleaning apparatus which shall perform the various functions of cleaning, extracting, drying and deodorizing in a series of successive operations without necessitating the transfer or removal of the articles to be cleaned from the cylinder or basket in which they are initially placed.

Another object of the invention is the provision of means for efficiently and economically reclaiming the cleaning solvent employed in the process. Other objects of the invention are the provision of an improved construction of the cleaning cylinder or basket, the shell enclosing said basket and the supporting structure therefor; the incorporation of a heating unit in said shell; the provision of a trap for absorbing moisture extracted from the articles cleaned, and reducing to a minimum the corrosive effects due to the circulation of such moisture through the apparatus, and the provision of a single unit including a lint trap, condenser and condensate sump.

To the accomplishment of the foregoing and related ends, said invention, then, consists of the means hereinafter fully described and particularly pointed out in the claims. The annexed drawings and the following description set forth in detail certain means and one mode of carrying out the invention, such disclosed means and mode illustrating, however, but one of various ways in which the principle of the invention may be used.

In said annexed drawings:

Fig. 1 is a diagrammatic view of the apparatus and the arrangement of the piping therefor, the upper portion of the view showing certain parts of the apparatus in front elevation and the lower portion of the view showing certain other parts of the apparatus in plan; Fig. 2 is a longitudinal cross sectional view of the washer; Fig. 3 is a transverse cross sectional view of the washer; Figs. 4 to 8 inclusive are detail views of the washer construction; Figs. 9 to 12 inclusive are detail views of the lint trap, condenser, and condensate sump construction; and Figs. 13 to 15 inclusive are detail views of the solvent trap construction.

The apparatus as illustrated more or less diagrammatically in Fig. 1 comprises solvent storage

tanks 1 and 2, a solvent still 3 interposed between the storage tanks, a condenser 4 mounted on the still, a filter 5, a combination washer and heater 6, a solvent trap 7, a pump 8, a combination lint trap, condenser and condensate sump 9, and a fan 10, all of which are interconnected by piping to form a continuous circuit as will be hereinafter explained.

In addition there are provided suitable valves, sight glasses, couplings, motors and electrical equipment, the location and nature of which will appear as the description proceeds.

The combination washer and heater unit 6 is shown more clearly in Figs. 2 to 8 inclusive. This unit includes a supporting structure comprising pairs of spaced apart end plates 11 and 12 which rest upon and are welded to a base plate or platform 13 and are connected by spaced front and rear plates 14 and 15 respectively. Secured as by welding to the upper edges of end plates 12 and front and rear plates 14 and 15 are pillow block bearing supporting plates 16, which terminate short of the end plates 11, the resulting space being taken up by opposite sides 17 and 18 of a rectangular supporting frame 19, which is secured as by welding to the upper edges of plates 11, 14 and 15 and the inner edges of plates 16. The upper edges of the sides 17 and 18 of supporting frame 19 are provided with semi-circular recesses 20 in which are received stuffing boxes 21 provided with the usual adjustable glands 22 and stuffing or packing 23. The frame 19 serves as a support for the outturned horizontal flange 24 of the semi-cylindrical lower half 25 of the washer shell or housing, this half of the washer shell being provided in its lowermost portion with a longitudinally extending sump 26. Sump 26 is in communication with a drain pipe 27 which extends through the end plates 11 and 12. Above the lower half 25 of the washer shell is positioned the upper half 28 of the washer shell or housing, this half being likewise provided with an outturned flange 29 which rests upon, but is separated from, the flange 24 by a gasket 30. A sectional frame consisting of pair of U-shaped frame members 31 is positioned on the flange 29, and screws 32 are provided to secure the frame and the upper and lower halves of the washer shell to each other as well as to the supporting frame 19. The upper half 28 of the washer shell has a rectangular opening 33 through which the articles to be cleaned are adapted to be passed. This opening is adapted to be closed by the loading door 34 which is mounted for pivotal movement about pins 35 and is adapted to be held in

- closed position by means of latches 36. The door 34 has secured to its inner surface a gasket 36 and a lining plate 37 which is smaller than the gasket and therefore leaves the marginal portion 5 of the gasket exposed, such exposed marginal portion of the gasket engaging the L-shaped flange of the shell 28. Flange 38 embraces a frame 39 which is mounted on the shell 28.
- The upper half 28 of the washer shell, instead 10 of being made substantially semi-cylindrical as is the lower half of the shell, has its rear portion formed to provide a chamber or compartment 40 which is separated from the main portion of the shell by means of a partition plate or baffle 41, provided with a series of longitudinally spaced openings 42. A U-shaped heater coil 43 extends longitudinally through the compartment 40 and is provided with an inlet 44 and an outlet 45 for steam or other suitable heating medium. The 15 function of this heater will be presently described.
- The washer proper comprises a cylindrical basket 46 having a multiplicity of perforations 47 and imperforate heads 48. The heads 48 have riveted thereto reinforcing conical members 49 to 20 which are welded tubular members 50 into which extend trunnions 51. The members 50 pass through the stuffing boxes 21, and the trunnions are suitably journaled in pillow block bearings 52 which are supported by the plates 16. Secured 25 to the interior surface of the basket 46 and extending longitudinally thereof are perforated baffles 53 of U-shaped cross section. The basket 46 is provided with an opening 46a through which the articles to be cleaned are introduced into the basket, and this opening is adapted to be closed 30 by a door 46b which, as shown in Figs. 2 and 7, is slidable circumferentially of the basket in guides 46c secured to the basket adjacent the opening 46a. This door is provided with a manually operable latching device (not shown) whereby the door is positively held in either closed or open 35 position.
- The conduit 27 which extends from the lower half of the washer shell is in communication with 40 an uptake conduit 54 which in turn is in communication with the lint trap and condenser unit 9, the detail construction of which will now be described, reference being had particularly to Figs. 2, 9, 10, 11, and 12.
50. The condenser comprises a cylindrical casing 55, closed at the bottom by a flanged disc 56 and at the top by the casing 57 of a fan 58, an open-ended tube 59, which is secured to the casing 57, serving to establish communication between the 55 interior of casings 55 and 57. Surrounding the lower end of tube 59 but spaced therefrom is a condenser coil 60 provided with a water inlet 61 and a water outlet 62. An inclined bulkhead or baffle plate 63 is disposed beneath the condenser 60 coil, and a sight glass 64 permits the condensate which drips over the plate 63 into the sump below to be observed. An outlet 65 is provided for the removal of the condensate which has collected on the bottom 56. The casing 55 has secured thereto 65 adjacent its front end a horizontally disposed cylindrical casing 66, with which the uptake conduit 54 communicates. Casing 55 is also provided with a circular opening 67 which is concentric with the casing 66, and surrounding this opening and secured to the casing 55 is a collar 68. Collar 68 provides a support for a lint trap which consists of a pair of concentric suitably reinforced cup-shaped screens 69 and 70, the inner screen 70 being 70 preferably of a coarser mesh than the outer screen 69. The construction of the lint trap is

such that it may be readily slipped off the collar 68 when it is desired to remove the trap. In order to gain access to the lint trap for the purpose of inspecting or removing same, a cover 71 is provided, this cover being normally in engagement with a gasket ring 72 at the base of an annular member 73 which is welded or otherwise secured to the casing 66 adjacent the end thereof. An air-tight engagement of the cover with the gasket is secured by means of a toggle-action locking device comprising a lever 74 which is pivoted to the casing 66 as at 75, and a yoke 76 which is pivoted to a lug 77 extending from the cover 71 and to the ends of the lever 74. By moving the lever 74 to the dotted line position shown in Fig. 11, the cover 71 is released and may be moved aside so as to permit access to the lint trap. The fan 58 is adapted to be driven by a motor 78 which is mounted on the casing 57. When a gate valve 79 is open, air blown by the fan 58 enters the washer shell. Auxiliary 20 gate valves 80 and 81 are also provided for the purpose of opening the washer shell and fan casing respectively to the atmosphere.

The solvent trap 7 is shown most clearly in Figs. 13 to 15 inclusive, and comprises a cylindrical casing 82 having an inlet 83 and an outlet 84, and closed at the bottom as by a flanged disc 85. Supported on the disc 85 is a removable filter unit comprising a perforated plate 86 having an up-standing flange 87 at its edge, said plate having 30 secured thereto a pair of vertically extending screens 88, between which is interposed a suitable moisture absorbent 89 such, for example, as cotton waste. The filter unit is so disposed that the screens 88 and interposed cotton waste form a 35 wall extending diametrically across the casing 82, so that all liquid which enters the inlet 83 must pass through this wall before reaching the outlet 84. The casing 82 is normally closed at the top by a cover 90 which is similar in all respects to 40 the cover 71 of the casing 66 and is adapted to be locked in closed position by toggle means similar to that employed for locking the cover 71.

The operation of the apparatus will now be described, reference being had particularly to the 45 diagrammatic view of Fig. 1.

The apparatus has been designed particularly with a view to the use of carbon tetrachloride, trichlorethylene, and other non-inflammable, non-explosive cleaning solvents, such solvents being capable of being evaporated without residual odors and of cleaning the most delicate fabrics without injury thereto. Other advantages of such solvents are that they do not separate on fractional distillation and may therefore be redistilled 55 and used over and over with extremely slight loss.

In filling the apparatus with the solvent, carbon tetrachloride for example, all of the valves are closed and a connection is established between the solvent drum (not shown) and valve 100. Valves 100, 101 and 102 are then opened and the solvent forced by motor driven pump 8 into storage tank 2. After tank 2 is filled, valve 102 is closed and valve 103 opened and tank 1 is filled. The pump is then stopped and the open valves closed.

The filter 5 is then filled with solvent. This is accomplished by opening valves 103 and 104, thereby permitting the solvent to flow from tank 2 into the lower half 25 of the washer shell. Valve 102 is then closed and valve 105 and air release petcock 106 on top of the filter opened. Pump 8 is then started and pressure gauge 107 observed. When the filter is full, the solvent will overflow through petcock 106, and the pressure gauge indicate an increased pressure. 75

Pump 8 is then stopped and petcock 106 and all the valves are closed. Air vent 108 is opened.

The basket 46 is then loaded with a predetermined weight of articles to be cleaned, it being desirable not to load the basket more than approximately two-thirds of its volume capacity. Valves 102 and 104 are then opened and the washer shell and basket filled with solvent to a predetermined level. Valve 102 is then closed, valves 105 and 109 opened and pump 8 started. The basket is then rotated at a slow speed; i. e., about 25 R. P. M., by motor 110 through reduction gear enclosed in housing 111, alternately in each direction for periods of about twenty seconds. During this washing process, the solvent is being continuously drawn from sump 26 through conduit 27 and outlet 112 into inlet 83 of the solvent trap, through the filter unit in the solvent trap, through outlet 84, through the filter 5 and back into the washer shell. In this manner dirt and other foreign matter are removed from the articles in the basket and deposited in the filter so that the articles are always being washed in clean solvent. When the solvent appears clear through the sight glass 113, valve 102 is opened, valve 104 closed, and the solvent pumped into tank 2. When the sight glass 113 shows that solvent is no longer passing therethrough, valve 101 is opened, valves 105 and 109 closed, and rotation of the basket stopped. The washing period varies from about ten to fifteen minutes according to the nature of the load.

With the pump still operating, the basket is rotated in one direction at high speed, i. e., about 500 R. P. M., for about three to five minutes, so as to extract as much solvent as possible from the washer and articles therein. This operation is generally designated as "extraction". After this operation the basket and pump are stopped and the load is ready for drying.

The small amount of solvent remaining in the articles is recovered during the drying operation. For this purpose, valve 79 is opened and valves 80 and 81 closed and the basket rotated at low speed as in the washing operation, and the fan 58 set in operation. At the same time, steam is introduced through valve 115 into inlet 44 passing through the heater coil 43 and out through the outlet 45. This steam heats the air which is blown into the compartment 40 of the washer shell and the heated air issues from the openings 42 and into the washer basket vaporizing the remaining solvent in the articles. The vapor laden air passes through conduit 27 and uptake conduit 54 and enters the casing 66. Any lint which is carried by the stream of air is trapped by and deposited on the screen 69 which is preferably cleaned after each cleaning cycle. The vapor laden air then passes downwardly into casing 55, the vaporized solvent being condensed by the coil 60 and falling on the bulkhead 63. The vapor free air then passes upwardly through tube 59 and is recirculated through the washer by the fan. The recovery of the vaporized solvent may be observed through the sight glass 64, and when solvent ceases to drip from the bulkhead 63, the drying is completed. The drying operation usually requires from about ten to thirty minutes, depending upon the nature of the load, and at the close thereof, the flow of steam through the heater coil is stopped as well as the flow of water through the condenser coil. Periodically, the condensate at the bottom of casing 55 is removed by

pumping it through outlet 65 and valve 116 back into one of the storage tanks.

Following the drying operation, the articles are deodorized or freshened, this being accomplished by closing valve 79 and opening valves 80 and 81, the rotation of the basket and operation of the fan being continued as in the drying operation. This operation is continued for about three minutes during which cold air is drawn into the washer basket through the lint trap and condenser and blown out through the opening of valve 81. Following this operation, the articles are removed from the basket.

After the last load has been washed, all of the solvent except that in the filter is pumped into the storage tanks and all of the valves are then closed.

When the solvent attains a dark amber color due to the dissolved greases, fats and oils, it may be distilled. This is accomplished by opening valves 102 or 103 and 104, thereby draining the solvent from the storage tanks into the washer. Valve 102 or 103, whichever has been opened, is closed and valves 101 and 117 are opened and the pump 8 started, thereby pumping the solvent into the still 3. Valve 118 or 119 depending on which of the storage tanks is empty is then opened and water admitted into the coil in condenser 4. Steam is then admitted into the still through valve 120 and the solvent vaporized, passing upwardly into the condenser. The condensed solvent may be observed as it flows past the sight glass 121 or 122. Sludge may be removed from the still through valve 123. Provision is also made for draining and cleaning the filter 5. If all of the valves have been previously closed, valves 109 and 124 and petcock 108 are opened, all of the solvent in the filter being thus drained into the washer, entering the conduit 27 at the opening 125. The open valves and petcock are then closed. Valves 101 and 117 are then opened, and the drained solvent pumped into the still. The pump is then stopped, all valves closed, and valves 105 and 126 opened. Steam is then admitted into a coil (not shown) in the lower portion of filter 5 through valve 127, thereby evaporating the solvent from the muck in the filter, the vaporizing solvent passing through valve 126 and conduit 128 into the condenser 9, where it is condensed and recovered in the same manner as the condensate from the washer. The clean out door 129 of the filter may then be opened and the dry residue scraped out.

All of the parts of the apparatus with which the solvent is in contact during the various operations are preferably constructed from nickel, which is highly resistant to the corrosive action of carbon tetrachloride.

Among other advantages of providing a horizontally split shell and separate supporting frame therefor, may be enumerated the following: (1) The assembly of the shell as well as the removal of the upper half thereof for inspection and removal of the basket are greatly facilitated. (2) All of the load, except the weight of the solvent used in washing, is carried outside of the basket on rigid bearing supports, thereby permitting the washer shell to be made of light gauge sheets. (3) The shell being made of light gauge material permits the attainment of rapid changes of temperature during the injection of hot air in the drying operation and of cold air during the freshening operation. Due to the light construction and design of the shell, it does not absorb a great deal

of heat during the drying operation and consequently cools very rapidly for the next washing operation. In this connection it may also be noted (see Figs. 5 and 6) that except for the flange 24, the washer shell does not touch the supporting structure which may be of steel and consequently very little heat is conducted from the shell to such supporting structure. The corrosive effect upon metals of carbon tetrachloride in combination with water or moisture increases as the temperature rises. Consequently it is of the utmost importance that the washing operation be conducted at as low a temperature as possible, and such temperature as above stated is easily attained as a result of the present construction. (4) The light gauge construction of the washer shell permits the use of the novel light weight loading door which has been previously described and which may be curved to the same contour as the shell and stretched tightly over the door opening with small light weight clamping bolts.

Among other advantages of incorporating the heater as an integral part of the washer shell may be mentioned the following: (1) The elimination of long air pipe connections and the conduction of heat in close proximity to the washer during the drying operation, thereby obtaining rapid drying of the articles being cleaned. (2) It permits the hot air to be brought into the top of the washer shell and removed at the bottom, thereby accelerating the drying operation, since air laden with solvent fumes is heavy and tends to settle to the bottom of the washer shell. The natural flow of solvent laden air being from the top of the shell to the bottom, this condition is best attained by placing the heater at the top of and inside of the washer shell. (3) The wall of cotton waste in the solvent trap 7 is particularly effective in absorbing the moisture extracted from the articles during the washing and extracting operations, thereby reducing to a minimum the corrosive effect of carbon tetrachloride in combination with moisture. The absorption of this moisture also tends to increase the speed and efficiency of the subsequent drying operation. This wall of waste also removes much of the lint and any foreign mat-

ter such as buttons, pins, etc. which might otherwise remain in the solvent. The flanged perforated plate 86 of the filter unit forms a basket for foreign matter and prevents it from entering the pump.

By incorporating the lint trap condenser and condensate sump as parts of an integral structure, the use of long air pipes is eliminated and heat losses avoided. The induction of the solvent laden air into the top of the condenser casing about the tube 59 and the reversal of the direction of the air flow by the fan by taking the air from the center of the condenser near the lower end thereof tends to precipitate the condensed solvent onto the plate 63, thereby aiding in the attainment of rapid and efficient drying.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In a dry cleaning apparatus, a substantially rectangular supporting frame, a washer shell supported on said frame, said shell comprising a semi-cylindrical lower portion having an outwardly extending flange resting on said frame and an upper portion having an outwardly extending flange disposed above said first-named flange, a sectional frame mounted on said second-named flange and means for securing said sectional frame to said supporting frame.

2. In a dry cleaning apparatus, a washer shell comprising a substantially cylindrical member having an enlargement in the upper portion thereof formed by integral portions of said member which extend tangentially therefrom, a perforated partition plate interconnecting said tangentially extending portions of said member and separating said enlargement from the balance of the cylindrical member, a U-shaped tubular member disposed in said enlargement, means for circulating steam through said tubular member and means for blowing air over said tubular member and into said shell.

CHARLES G. WATSON.
